(57) **CLAIM**

The ornamental design for a connector for a construction kit, as shown and described.

DESCRIPTION

FIG. 1 is a perspective view of a connector for a construction kit showing my new design;

FIG. 2 is a front view of the connector for a construction kit shown in FIG. 1;

FIG. 3 is a top view of the connector for a construction kit shown in FIG. 1;

FIG. 4 is a bottom view of the connector for a construction kit shown in FIG. 1;

FIG. 5 is a right side view of the connector for a construction kit shown in FIG. 1;

FIG. 6 is a back view of the connector for a construction kit shown in FIG. 1; and,

FIG. 7 is a left side view of the connector for a construction kit shown in FIG. 1.
